(57) **CLAIM**

The ornamental design for motorcycle tank shaped luggage, as shown and described.

DESCRIPTION

FIG. 1 is a perspective view of motorcycle tank shaped luggage showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of the eagle in FIGS. 1, 4, and 5 is illustrative of environment only and forms no part of the claimed design. The broken line showing of the caps in FIGS. 1-6 and the straps in FIGS. 1-7 is also illustrative of environment, merely showing the types of ornamentation and straps which may be used, and forms no part of the claimed design.

The broken lines in a regular dash-dash-dash pattern, appearing in all figures, indicate stitching. These lines do form part of the claimed design.
